UNITED STATES PATENT OFFICE.

CARL BREER, OF SUMMIT, NEW JERSEY.

DISH-HOLDING TRAY.

Application filed July 21, 1920. Serial No. 397,878.

To all whom it may concern:

Be it known that I, CARL BREER, a citizen of the United States, residing at Summit, in the county of Union and State of New Jersey, have invented new and useful Improvements in Dish-Holding Trays, of which the following is a specification.

This holding tray is especially designed for use in dish washing machines and is so constructed as to hold plates and similar dishes in proper relation and position to fully expose the surfaces so that they may be thoroughly washed. In carrying out the invention the frame is ordinarily formed of wire and is provided with upright partitions. In the present construction these partitions are bent so as to conform or follow in a general way the dished surfaces of the dishes. In this way a greater number of dishes can be accommodated in the same space and still have all the surfaces exposed for washing, in other words, while the dishes are held apart a nesting of the dishes is to some extent made possible.

The invention is illustrated in the accompanying drawings as follows:

Fig. 1 shows a plan view of the tray.

Fig. 2 an end elevation of the tray.

Fig. 3 a side elevation.

Wire is bent into rectangular shape and forms the upper edge 1 of the frame. A wire 2 similarly bent forms the lower corner or base of the frame. These upper and lower wires are connected by the loops forming handles 3, the lower ends of the loops being welded to the wire 2 and the intermediate portions of the loops being welded to the upper wire 1. These loops 3 form the handles for the tray. A wire netting 4 is drawn across the bottom of the tray and shaped to conform to the sides and the upper ends of the wires forming the netting are bent over the wire 1 at 5.

Rods 6 extend lengthwise of the tray and are preferably arranged slightly off center so as to leave one part of the tray open for odd-shaped dishes. The rods 6 have the downwardly turned ends which are welded to the ends of the bottom frame wire 2.

Dish supports 8 are formed of wire. These supports have the upright portions 9 with the connecting loop 10 at the top. Lateral extensions 11 are formed at the bottoms of the uprights 9 and the outer ends of these extensions are turned upwardly at 12 and the ends of the wires forming the uprights

are welded to the underside of the rods 6. The wires 7 are bent at 13 so that the upper ends are preferably vertical and the lower ends are slightly inclined so that an interposed dish as indicated in dash lines at 14 will be more readily received between the supports, in other words, the supports are bent to follow in a general way the dished formation of the dishes so that the dishes may to some extent nest. At the same time the dishes are maintained so as to expose all surfaces so that they may be thoroughly cleaned.

It will be noted also that the lateral extensions on the supports form torsion members which permit of a slight movement of the uprights so as to accommodate different sizes of dishes. To this end also it is preferable to vary the spacing between the uprights as indicated particularly in Fig. 3. By bending the members downwardly from the rods the rods are placed up sufficiently to locate the round dishes axially and the supports are carried down to a position that will engage the lower part of the dish so as to relieve the dishes of strain.

What I claim as new is:

1. In a dish-holding tray, the combination of a frame; and upright dish supports spaced to permit the insertion of dishes between them, said supports being formed of wire with upright sides looped at the top and secured at the bottom to the frame, the upright sides being bent toward the next adjacent support at one side and away from the support at the opposite side to accommodate the dished surface of a dish.

2. In a dish-holding tray, the combination of a frame; and upright dish supports spaced to permit the insertion of dishes between them, said supports being formed of wire with upright sides and looped top and having lateral extensions from the wires at the bottom forming torsion members on which the uprights may swing, the ends of said torsion members being secured to the frame.

3. In a dish-holding tray, the combination of a frame; longitudinal rods secured to parts of the frame; and upright dish supports formed of wire with upright sides between the rods, the lower ends of said wires being provided with lateral extensions secured to said rods, said extensions forming torsion members on which the uprights may swing.

4. In a dish-holding tray, the combination of a frame; longitudinal rods extending above the bottom of the tray and secured to the frame; dish securing uprights formed of wire having upwardly extending sides connected at the top; and lateral extensions at the bottoms of the uprights, the outer ends of the extensions being up-turned and secured to the rods and the sides of the wire being bent toward the next adjacent support 10 at one side and away from the support at the opposite side to accommodate the dished surfaces of a dish.
5. In testimony whereof I have hereunto set my hand.

CARL BREER.
